ALL WELDED HIGH-PRESSURE WATER TUBE BOILER

Herman M. Wolter, San Francisco, Calif.

Application May 1, 1943, Serial No. 485,557

3 Claims. (Cl. 122—255)

An object of my invention is to provide an all welded high pressure water tube boiler in which the water is rapidly circulated due to the particular arrangement of the boiler tubes and by mechanical circulation. The rapid moving water in the boiler tubes when subjected to heat from the flame of a burner generates steam rapidly so that the boiler operates practically as a flash boiler while having the added advantage of a water reserve and plenty of steam to meet almost any condition. The circulation of the water in the boiler is augmented by causing the feed water to enter the boiler in a particular manner.

A further object of my invention is to provide a boiler of the type described in which the formation of scale in the boiler tubes is practically eliminated. This is accomplished by either disposing the boiler tubes in a vertical or an inclined position and moving water rapidly through the tubes so that any sediment will gravitate to the lower headers and from these pass into mud drums that are disposed below the lower headers and exterior of the boiler wall.

Still a further object of my invention is to provide a boiler of the type described in which an explosion is practically impossible to take place. The boiler is adapted for use in automobiles, trucks, busses, motor boats, or any vehicle, and it can also be used in mobile or stationary plants.

Other objects and advantages will appear in the following specification, and the novel features of the device will be particularly pointed out in the appended claims.

My invention is illustrated in the accompanying drawings forming a part of this application, in which

Figure 1 is a rear elevation of the boiler with the rear boiler wall removed;

Figure 2 is a top plan view of the boiler with the top boiler wall removed;

Figure 3 is a longitudinal section taken along the line 3—3 of Figure 1;

Figure 4 is a longitudinal section of the water pump connections and is taken substantially along the line 4—4 of Figure 1;

Figure 5 is a section taken substantially along the line 5—5 of Figure 2; and

Figure 6 is a vertical section through a modified form of the device.

While I have shown only the preferred forms of my invention, it should be understood that various changes or modifications may be made within the scope of the appended claims without departing from the spirit of the invention.

In carrying out my invention, I provide a steam

boiler that has side walls 1 and 2, front and rear walls 3 and 4, a bottom wall 5, and a top wall, not shown. The walls may be formed of any desired material that has a high refractory and insulating quality. Along the side wall, and adjacent to the bottom wall 5, I dispose a lower or bottom header A, see Figure 1. Both Figures 1 and 3 illustrate the lower header A connected to an upper or top header B by a plurality of vertical tubes C. The vertical tubes C are of uniform diameter throughout their height and have conical ends 6 and 7 that are welded to and communicate with the lower and upper headers respectively. The headers and vertical tubes may be made of a size sufficient to develop the amount of steam desired.

Adjacent to the other wall 2, a second pair of lower and upper headers A¹ and B¹ are disposed and vertical tubes C¹ interconnect these last two headers together as indicated in Figures 1, 2 and 5. A like number of vertical tubes C and C¹ are arranged on opposite sides of the boiler. Figures 1, 2 and 3 indicate that the tubes C and C¹ lying in the same transverse planes form pairs of tubes and each pair of tubes is interconnected by two groups of inclined boiler tubes, these two groups being indicated at D and E in the same figures. The tubes in group D have their lower inlet ends 8 communicating with the vertical tube C and 25 their higher outlet ends 9 communicating with the vertical tube C¹. The opposite is true of the tubes in group E for they have their lower inlet ends 10 communicating with the vertical tube C¹ and their higher outlet ends 11 communicating with the vertical tube C.

Each pair of vertical pipes C and C¹ has the two groups of inclined steam generating tubes D and E. This is clearly illustrated in Figures 1, 2 and 3. The upper ends 9 and 11 of the inclined tube groups D and E are disposed well below the water level 12 in the vertical tubes C and C¹ so that the inclined tubes will be filled with water at all times. If the boiler is used in a vehicle that climbs a steep grade, such as an automobile, the height of water in the vertical tubes C and C¹ is such that regardless of the angular tilt of the entire boiler, both sets of inclined tubes will remain filled with water.

The means for feeding water to the headers, vertical tubes, and inclined tubes is shown in Figures 1, 2, 3 and 5. Figure 2 shows the feed water pipe 13 communicating with a check valve 14. A T or Y 15 places the valve 14 in communication with two water preheater coils F and F¹. The water preheater coils are arranged near the top

of the boiler, see Figure 1. The coils F and F¹ communicate with vertically extended water legs or pipes G and G¹ and the latter are disposed at the front of the boiler and communicate with the front ends of the lower headers A and A¹. In this way preheated water is delivered to the lower headers. The pipes G and G¹ have nozzles at the points where the heated water enters the lower headers. The entrance of the water through the nozzles causes the water to circulate in the lower headers in a manner more completely described hereinafter.

A burner, not shown, heats the water in the headers, vertical tubes, inclined tubes and water circulating tubes K and K¹ hereinafter described. The burner is preferably of the atomizing blower type and is disposed at the front end of the boiler although it may be disposed at the rear if desired. Steam is generated in the inclined tubes and in the vertical tubes the steam rising above the water line 12 in the last named tubes and passing into the top headers B and B¹. Downwardly inclined steam conveying pipes H and H¹ lead from the top headers to a centrally disposed steam drum 16. The drum is placed above the inclined steam generating pipes in a hot portion of the boiler, but not in too hot a portion. An outlet pipe 17 delivers semi-superheated steam at the proper temperature from the drum for efficient operation of any steam driven unit, not shown. By placing the drum 16 at the position shown in Figure 1, I eliminate the usual troubles experienced with superheaters where they are placed too close to the hottest part of the boiler.

I have found that steam is generated more rapidly if the water in the boiler is kept circulating. The inclined steam generator tubes D and E cause the water to circulate because the steam will quickly rise to the top of tubes and the difference in weight between hot and cold water will cause a water flow from the lower to the upper ends of the inclined tubes. A turbulence in the water is created by the cross flows of water in the oppositely inclined groups or set of tubes, both groups communicating with the same pair of vertical tubes. Each pair of tubes with its two groups of oppositely inclined tubes act as an individual circulating boiler. This arrangement also results in a movement of the water from side to side of the boiler where it will be more rapidly heated as it moves across the center of the boiler or fire chamber.

To further the movement of water, I provide a water circulating pump 18, see Figures 1, 2 and 4. Pipes J and J¹, see Figure 2, communicate with the rear ends of the lower headers A and A¹ and convey water to the pump 18, the water passing through a check valve 19, see Figure 4. The pump forces the water through two water coils K and K¹, see Figure 1, where the temperature of the water is raised, and then the water is delivered to the front ends of the lower headers at 20 where nozzles (not shown) are provided for forcing the water in the lower headers toward the rear of the boiler. The feed water jets and the jets at the places 20 face in the same direction so that the flow of water from both jets will aid each other. The pressure of the water on both sides of the pump is the same so that little power is needed to circulate the water. The pump 18 is shown inside the boiler although in actual practice it will be disposed outside of the boiler.

The pump accelerates the water circulation in addition to the flow of water from one vertical

tube of a pair through the inclined tubes to the other vertical tube of the same pair. The steam rising in the vertical tubes promotes further water movement. The pump however, gives additional rapid circulation to the water, drawing the water from the rear ends of the lower headers and forcing it through coils to the front ends of the same headers. The fresh water entrance into the front ends of the lower headers helps the flow. The pressure of the incoming water is greater than the pressure in the boiler.

Since all of the tubes are either vertical or inclined, and since the water flows rapidly through the tubes, scale formation on the tubes is eliminated. Mud drums L and L¹ are provided below the lower headers A and A¹ and pipes 21 place them in communication with the headers so that any sediment will fall into the lower headers and thence into the mud drums. The mud drums are disposed outside of the boiler walls and are provided with blow off valves 22, see Figure 3. The blow off valves permit sediment to be blown out of the mud drums from time to time. They are merely opened and the boiler pressure is sufficient to effect a cleaning of all sediment from the mud drums.

All of the tubes are preferably made of seamless drawn tubing of a metal such as nichrome that is able to withstand high temperatures, extreme pressures and will resist corrosion. The inclined steam generating tubes D and E are always filled with water so as to prevent any trouble from expansion and contraction. The water level is high enough above the inclined tubes that an angular tilting of the boiler is possible and still the tubes will remain filled. This adapts the boiler for use in automobiles and other vehicles that are required to climb steep grades. The tilting of the boiler due to the vehicle climbing a steep grade will still keep the inclined tubes filled with water. Where the boiler height is immaterial, more inclined pipes can be used.

The tubes C, C¹, D and E, and all of the other tubes and pipes are enclosed within a fire chamber which comprises the walls of the boiler. These walls have a high refractory and insulating quality. Practically all of the heat units from the burner flame are absorbed by the boiler tubes and water to generate steam. The size of the boiler can be changed by increasing the size and/or number of both the vertical and inclined tubes and also the upper and lower headers and the steam drum. The boiler is of the quick firing and rapid steaming type. It is sturdy, durable, efficient and practically non-explosive. All of the tubes and pipes are welded together as a single unit. This adapts the boiler to be installed in any kind of a vehicle, or it can be used in a mobile or stationary plant.

In Figure 6, a sectional type boiler is illustrated. This boiler is identical in operation to the form shown in Figures 1 to 5 inclusive. The lower headers X are made up of tubular sections 23 with soft copper gaskets 24 disposed between the sections. In like manner the upper headers Y are made up of tubular sections 25 with soft copper gaskets 26 disposed therebetween. Tie rods 27 hold the lower sections 23 together and tie rods 28 secure the upper sections together. Vertical tubes Z extend between the sections 23 and 25 and are welded to these sections at 29 and 30. Except for the sectional feature, the boiler of Figure 6 is the same as the boiler already described and therefore no further description need be given except for the connections for the feed

and circulating water to the lower headers of the sectional boiler shown in Figure 6. The first or second section of each end of the lower headers will have **T** or **Y** connections with the feed water legs **G** and **G¹** and the water circulating and heating coils **K** and **K¹**.

From the foregoing description of the various parts of the device, the operation may be readily understood. The feed water enters the boiler from pipe 13 under sufficient pressure to overcome the boiler pressure. The check valve 14 prevents any back flow. The feed water is heated in the water pre-heating coils **F** and **F¹** and then flows down the water legs **G** and **G¹**, entering the forward ends of the lower headers **A** and **A¹** through jets, not shown. The water is rapidly circulated in the boiler tubes due to the inclined tubes **D** and **E**. The circulation of the water is also mechanically accomplished by the pump 18 that draws water from the rear ends of the lower headers and forces it through the lower heating coils **K** and **K¹** before sending it back into the front ends of the lower headers. Water jets at the points 20 feed the heated water into the lower headers in the same direction as the feed water issuing from the water legs **G** and **G¹**. Both streams of water aid each other and increase the circulation.

The steam generated in the tubes passes to the steam drum where it is semi-superheated before being delivered to the steam outlet pipe 17. Any sediment falls to the mud drums **L** and **L¹** where it is blown out from time to time. Where height is not a dominant factor, it is possible to add more inclined tubes and thus give greater heating surface for the water and produce greater efficiency. The boiler is of the high pressure type and can operate on a steam pressure up to one thousand pounds. If superheated steam is desired, the steam outlet pipe 17 or another pipe can be led from the steam drum down into the fire chamber where the burner flame will raise the temperature of the steam to the desired extent.

I claim:

1. A steam boiler comprising a fire chamber, lower and upper headers disposed on each side of the fire chamber, a plurality of vertical steam generating tubes disposed on both sides of the fire chamber, the vertical tubes on one side interconnecting the headers on the same side and the vertical tubes on the other side also interconnecting the lower and upper headers on the last-named side, the vertical tubes on opposite sides being arranged in pairs, two sets of inclined steam generating tubes interconnecting each pair of transversely opposed vertical tubes, one set of the inclined tubes being inclined oppositely to the other set connected to the same pair of vertical tubes, whereby a transverse flow of water from the vertical tubes on one side to those on the other side takes place through the inclined tubes, means for delivering feed water to the lower headers under sufficient pressure to offset the pressure in the boiler, a steam drum connected to the upper headers for receiving steam generated by the vertical and inclined tubes, and means for circulating the water in the lower headers including a pump communicating with an end of each lower header for drawing water therefrom, and water heating coils for receiving the water from the

pump and for delivering the water to the other ends of the lower headers for completing the circuit.

5 2. A steam boiler comprising a fire chamber, lower and upper headers disposed on each side of the fire chamber, a plurality of vertical steam generating tubes disposed on both sides of the fire chamber, the vertical tubes on one side interconnecting the headers on the same side and the vertical tubes on the other side also interconnecting the lower and upper headers on the last-named side, the vertical tubes on opposite sides being arranged in pairs, two sets of inclined steam generating tubes interconnecting each pair of transversely opposed vertical tubes, one set of the inclined tubes being inclined oppositely to the other set connected to the same pair of vertical tubes, whereby a transverse flow of water from the vertical tubes on one side to those on the other side takes place through the inclined tubes, means for delivering feed water to the lower headers under sufficient pressure to offset the pressure in the boiler, and a steam drum connected to the upper headers for receiving steam generated by the vertical and inclined tubes, said feed water delivery means including pre-heating coils that connect with the lower headers for pre-heating the feed water before it reaches the lower headers, said means also delivering the feed water into the lower headers so that the water in the headers will be caused to flow along the lengths of the headers, thus aiding in circulating the water in the boiler, and auxiliary means for circulating the water in the lower headers including a pump communicating with an end of each lower header disposed opposite to the feed water entrance to the headers for drawing water therefrom, and water heating coils for receiving the water from the pump and for delivering the water 30 to the other ends of the lower headers in a direction to be aided by the flow of feed water into the headers, whereby the circulation of water in the boiler is further aided.

3. A steam boiler comprising a fire chamber, lower and upper headers disposed on opposite sides of the fire chamber a plurality of vertical steam generating tubes connecting the lower header on one side of the fire chamber with the upper header on the same side, a like number of vertical tubes connecting the lower header on the opposite side of the fire chamber with the upper header on the same side, each vertical tube on one side being disposed transversely opposite from a similarly positioned tube on the opposite side, the two tubes so constituting a pair, a set of inclined steam generating tubes connected to each pair of vertical tubes, a second set of steam generating tubes inclined in an opposite direction to the first set and being connected to each pair of vertical tubes so that each pair of vertical tubes will have inclined tubes extending in opposite directions, means for feeding water to the lower headers, a steam drum connected to the upper headers and being disposed above the sets of oppositely inclined tubes, and a pump for circulating the water in the lower headers independent of any water circulation resulting from the feed water entering the lower headers.

HERMAN M. WOLTER.
